United States Patent Office.

PAUL DENNIS, OF SCHUYLERVILLE, NEW YORK, ASSIGNOR TO HIMSELF AND GEORGE LEGGETTE, OF THE SAME PLACE.

Letters Patent No. 74,805, dated February 25, 1868.

IMPROVED GATE-HINGE.

The Schedule referred to in these Letters Patent and making part of the same.

TO ALL WHOM IT MAY CONCERN:

Be it known that I, PAUL DENNIS, of Schuylerville, in the county of Saratoga, and State of New York, have invented a new and improved Gate-Hinge; and I do hereby declare that the following is a full, clear, and exact description thereof, which will enable others skilled in the art to make and use the same, reference being had to the accompanying drawings, forming part of this specification.

This invention consists of an improved gate-hinge, and has for its object increased strength and durability of the hinge and diminution of the friction in opening and closing the gate. In the accompanying drawings—

Figure 1 is a top view of my improved hinge.

Figure 2 is a vertical section thereof at the line $z z$.

Figure 3, sheet 2, is a perspective view of the gate-hinge, showing the position of the gate, the latter being in red lines.

Similar letters of reference indicate like parts.

A is the roller; α its axis, having its bearings in the grooves $b b$ in the interior of the sides of the open-ended box B. The wings or sides of the box B extend above the roller, and serve as guides to the gate. The box B carries a pivot, C, which sets in the socket D of the hinge E. The hinge E may be a single bar secured in the ordinary manner, but I prefer a double-clasp hinge fastened to two sides of the gate-post. I also prefer casting the roller A and pin or axis α in one casting, and the box B, with its pivot C, also in one casting, as tending greatly to increase the strength of the entire hinge. The flanges $e e$ also serve to increase the strength of the hinge E, but are not an essential feature of my invention.

Having thus described my invention, I claim as new, and desire to secure by Letters Patent—

The construction of the gate-hinge, consisting of the forked portion D, having a socket in which the pintle C of the box B fits, said box carrying above the pintle, in the grooved guides b , the roller A, as herein described, for the purpose specified.
